BUTTONHOLE ATTACHMENT FOR SEWING MACHINES

James Hickey, Portland, Oreg.

Application November 13, 1944, Serial No. 563,221

6 Claims. (Cl. 112—77)

1

This invention relates to devices adapted to perform the necessary stitching in the finishing of buttonholes.

More specifically, this invention relates to removable buttonhole attachments suitable for use with an ordinary sewing machine.

Buttonhole attachments equipped to perform zig-zag stitching around a buttonhole are more or less common. However, I have found that a fault with a number of devices of this type is that they do not provide for double length zig-zag stitches at the ends of the hole or slit in the cloth. Such double length stitches are desirable for reinforcing the ends of the buttonhole and for preventing the buttonhole from stretching or tearing. Such double length stitching is provided for in some of the special buttonhole machines but these involve quite complicated mechanism and are generally not mere attachments for ordinary sewing machines.

The object of this invention is to provide means for performing such double length end stitching with a simple buttonhole attachment, suitable for use with ordinary sewing machines, whenever such double length stitching is desired.

A further object is to control the double length stitching, so that it may or may not be performed, and also arrange to have the double length stitching performed automatically when desired.

An additional object of this invention is to provide for such improvement in a simple, practical and inexpensive manner so that the improvement can be incorporated in ordinary buttonhole attachments at very small additional cost.

In the accompanying drawings:

Figure 1 is a view, in isometric perspective, of a portion of an ordinary sewing machine head with my improved attachment secured in place, and also showing a piece of cloth on which the desired buttonhole stitching has been performed.

Figure 2 is a medial longitudinal sectional elevation viewed from the far side of Figure 1;

Figure 3 is an elevation of the attachment viewed from the far side of Figure 1;

Figure 4 is a staggered plan section corresponding to the line 4—4 of Figure 3;

Figure 5 is a fragmentary transverse section corresponding to the line 5—5 of Figure 4, showing the end of the restriction bracket in normal raised position;

Figure 6 is a similar fragmentary transverse section but showing the restriction bracket in lowered position;

2

Figure 7 is a view in perspective of certain individual members in my device illustrating the same separated from each other for the sake of clarity but arranged more or less in their related order:

Figure 8 is a plan section taken on the line 8—8 of Figure 3;

Figure 9 is a fragmentary plan view of some of the bottom members of my device illustrating the operation of the restriction bracket when the bracket is in the raised position shown in Figure 5; and

Figure 10 is a similar fragmentary plan view illustrating the operation of the restriction bracket and stitch-control lever when the restriction bracket is in the lowered position of Figure 6.

Referring first to Figure 1, the buttonhole attachment is secured in the customary manner to 20 the sewing machine presser foot bar 11 after the usual cloth-engaging element has been removed from the base of the presser foot bar. The attachment carries its own cloth-engaging element 18 which rests on and engages the cloth 25 14 when the machine presser foot bar has been dropped to lowered position in the sewing machine head 10.

The cloth-engaging element 18 is in the usual form of a hollow rectangle and the sewing machine needle 13 passes through the opening in the same, the opening being wide enough to provide for the maximum length of zig-zag stroke as the cloth is moved back and forth under the sewing machine needle by the attachment. The cloth-engaging element 18 has the usual serrated bottom surface to grip the cloth and to move it back and forth under the needle, resulting in the familiar zig-zag buttonhole machine stitching.

40 The attachment includes an integral frame 15 having side portions and bottom connecting strips and also having a horizontally extending forked arm 16 which is connected to the presser foot bar 11 in the customary manner. The feed blade 17 (see also Figure 7) rests loosely in the frame 15, by which it is reciprocally and slidably supported, and the cloth-engaging element 18 is attached below the forward end of the feed blade 17 as usual. The feed blade 17 is formed with 45 a pair of longitudinal slots 17' and also has an integral slotted arm 19 at one side extending vertically upward.

A lever arm 20 (see Figures 1 and 3), pivotally mounted on the frame 15 for up and down movement, has a forked end 31 which is adapted

to be attached to the needle carrier 12 of the sewing machine and thus is reciprocated up and down with the movement of the needle carrier and needle 13. The arm 29 carries a pawl 35 (Figure 3) which engages a ratchet 34. The ratchet 34 is secured to a shaft 33 on which is also secured the central cam wheel 32. The periphery of the cam wheel 32 engages the upstanding lugs 31 (see also Figures 4 and 7) mounted in the stitch control lever 36. Thus reciprocation of the arm 29, by producing step by step rotation of the cam wheel 32, also produces corresponding reciprocation or oscillation sideways of the stitch control lever 36. A downwardly extending tongue 38 at the forward end of the stitch control lever 36 engages a slot in the feed blade 17. Consequently, the feed blade 17, and with it the cloth which is engaged by the element 18 of the feed blade, reciprocates sideways at each stroke of the needle, which results in the zig-zag stitch common to buttonhole machines and attachments.

The arm 29 (Figure 3) has a rear shoulder 30 which is adapted to engage a ratchet member 22, and the ratchet member 22 in turn is connected by means (not shown) to a shaft 21, and this part of the mechanism is so arranged as to produce slower step by step rotation of the shaft 21 as the arm 29 reciprocates.

A disk 20 secured to the end of shaft 21 adjacent the vertical arm 19 of the feed blade 17 (see Figures 1 and 4) has a crank pin 20' which engages the slot in the vertical arm 19. Thus, as the crank disk 20 rotates slowly, the feed blade is gradually moved longitudinally, first in one direction and then in the opposite direction, while at the same time the feed blade is constantly reciprocated sideways.

A cam disk 23, shown most clearly in Figures 4 and 7, is formed with two oppositely off-set similar portions so that nearly one-half of the periphery lies in one vertical plane while a similar portion of the periphery lies in another vertical plane spaced from the first. The periphery of this cam disk 23 engages a pair of upstanding lugs 26 (see Figures 2 and 8) carried on a lever 24, which is pivotally mounted at 25 and which in turn is connected to an adjustable lever arm 27. The forward end of lever arm 27 has a downwardly-extending tongue 28 which engages a slot 17' in the feed blade 17. This connection between cam disk 23 and feed blade 17 ordinarily causes the zig-zag stitching to be performed along one side of the buttonhole slit as the feed blade 17 is moved longitudinally in one direction and on the other side as the feed blade is moved longitudinally in the reverse direction.

The construction which I have described thus far is for the most part well known and common to a familiar type of buttonhole attachment. I shall now explain the particular improvements which I have developed.

The stitch control lever 36, the upstanding lugs 31 of which are engaged by the cam wheel 32, and which in turn transmits horizontal reciprocal movement sideways to the feed blade 17, is formed with an upwardly extending tongue 39 at the rear end. The upper half of this tongue is considerably narrowed as shown at 40 in Figure 7. A restriction bracket 41, the shape of which is also shown more clearly in Figure 7, carries a rear cross bar 43 which is provided with a slot 44. The length of the slot 44 is only slightly greater than the width of the lower half of the upstanding tongue 39. A slide arm 45 is mounted on one side of the restriction bracket

41 and has a finger grip or adjustment lug 47. The restriction bracket is hinged to the frame 15 for up and down movement (Figures 2, 3 and 4), and a spring 42 holds the bracket normally in the raised position shown in Figure 2 so that only the top portion 40 of the tongue 39 of the stitch control lever 36 will extend through the slot 44.

On the cam disk 23 I provide two pins 46 at diametrically opposite points near the periphery. These pins are so arranged as to engage the end of the slide arm 45 of the restriction bracket 41 alternately as the cam disk 23 is rotated. In other words, with each half rotation of the cam disk 23, one of the pins 46 will cause the restriction bracket 41 to be pushed down to lowered position temporarily, but as soon as the pin moves out of engagement with the arm 45 the spring 42 will cause the restriction bracket 41 to return to normal raised position. The cam disk 23 and the crank disk 20 are both mounted on the same shaft 21 and rotate in unison. The crank pin 20' of the crank disk 20 produces the longitudinal movement of the feed blade 17 as previously mentioned. The crank pin 20' is so arranged with respect to the pins 46 that when the crank pin 20' moves into the horizontal plane of the shaft 21, that is, when the feed blade 17 reaches the limit of its longitudinal movement in either direction, one of the pins 46 will engage the arm 45 and push the restriction bracket 41 into lowered position.

In Figure 5 the restriction bracket 41 is shown in normal raised position. In Figure 6 one of the pins 46 has been moved into engagement with the arm 45 and has pushed the restriction bracket 41 into lowered position. The effect of this change of position of the restriction bracket 41 will now be explained.

Referring to Figures 6 and 10, when the restriction bracket 41 is in lowered position with the wide portion of the tongue 39 of the stitch control lever 36 extending through slot 44, the rear of the stitch control lever 36 will be held against oscillation or reciprocal movement sideways. Consequently, the rotation of the cam wheel 32 will produce greater oscillation of the other end of the stitch control lever 36 from which the tongue 38 extends and thus will produce greater oscillation of the feed blade 17. But when the restriction bracket 41 is in the normal raised position shown in Figures 5 and 9 with only the narrow top portion 40 of the tongue 39 extending through slot 44, the rear end of the stitch control lever 36 will be moved sideways by the cam wheel 32 before the forward end of the stitch control lever 36 is moved, and consequently the subsequent oscillation of the forward end or tongue 38 will be reduced. Thus when the restriction bracket 41 is pushed to the lowered position of Figure 10, the feed blade 17 will be oscillated in a wider path than when the restriction bracket 41 is in the normal raised position of Figure 9. Since the restriction bracket 41 is pushed to lowered position when the feed blade 17 reaches the end of its longitudinal movement in either direction, the increased oscillation of the feed blade 17 at such times results in the desired double length stitches at each end of the buttonhole.

The principle on which my invention operates will be clear from Figures 9 and 10. In Figure 10 the pivotal point of the stitch control lever 36 is the rear end of the lever. In Figure 9 the actual pivotal point is first located at the front end and

then moves to the rear end when the rear end is temporarily held against further lateral movement in the same direction. Consequently, as previously explained, under this latter condition, the period during which the front end moves is reduced and the extent of movement of the front end of the lever 36 is correspondingly reduced.

In the finished buttonhole shown in the cloth 14 in Figure 1, this desired double length stitch is indicated at *z* at each end of the buttonhole, and the normal narrower intermediate zig-zag stitching along the two sides of the buttonhole which takes place when the restriction bracket is in raised position is indicated at *y* on both sides of the button hole.

If it is desired to dispense with the double length stitching *z* at the ends of the buttonhole, all that is necessary is to push the adjustment lug 41 of the arm 45 (Figures 1, 4 and 7) forward so that the rear end of the arm 45 will not be engaged by the pins 46. On the other hand, if it is desired to perform double width stitching only, for example, in mending or patching, instead of the usual buttonhole stitching, this can be done by pushing the adjustment lug 41 all the way back under a shoulder 48 (Figure 1) in the side of the frame which will then keep the restriction bracket continually in lowered position.

Various modifications could be made in my attachment within the scope of my invention and without departing from the main principle of providing means for changing the pivotal point of the stitch control lever or some equivalent member mounted for lateral oscillation and connected to the feed blade so as to modify the amount of the lateral oscillation imparted to the feed blade.

I claim:

1. In a buttonhole attachment for a sewing machine, a feed blade mounted for longitudinal and lateral movement, means for moving said feed blade longitudinally in alternate directions, a stitch control lever connected with said feed blade, cam means for producing lateral oscillation of said stitch lever and therewith of said feed blade, a restriction bracket associated with one end of said lever, an engaging element on said restriction bracket for holding said end of said lever against oscillation when said bracket is in full engaging position, whereby to increase the amount of oscillation of the opposite end of said lever and therewith the amount of oscillation of said blade, and means for moving said bracket into full engaging position whenever said blade reaches the end of its longitudinal movement in either direction.

2. In a buttonhole attachment for a sewing machine, a feed blade mounted for longitudinal and lateral movement, means for moving said feed blade longitudinally in alternate directions, a stitch control lever connected with said feed blade, cam means for producing lateral oscillation of said stitch lever and therewith of said feed blade, a restriction bracket associated with one end of said lever, an engaging element on said restriction bracket for holding said end of said lever against oscillation when said bracket is in full engaging position, whereby to increase the amount of oscillation of said blade, means connected with said first mentioned means for moving said bracket into full engaging position whenever said blade reaches the end of its longitudinal movement in either direction, and a spring acting normally to hold said bracket out of full engaging position when said blade is in intermediate longitudinal position.

3. In a buttonhole attachment of the character described, a feed blade mounted for longitudinal and lateral movement, a stitch control lever located above said feed blade, the forward end 10 of said lever connected with said feed blade, an upstanding tongue at the rear end of said lever, a restriction bracket located above said lever, said bracket hinged at its forward end for up and down movement, a cross bar on said bracket, said cross bar having a slot, the length of said slot corresponding approximately to the width of said upstanding tongue, whereby said bracket will prevent oscillation of the rear end of said lever when said bracket engages said upstanding tongue, a spring normally holding said bracket out of engagement with said upstanding tongue, a cam wheel engaging said lever between the forward and rear ends of said lever and adapted to produce lateral oscillation of said lever, means for 15 moving said blade longitudinally in alternate directions, associated means for pushing said bracket into lowered position whenever said blade reaches the end of its longitudinal movement in either direction, whereby the pushing of said bracket to lowered position will cause greater lateral oscillation of the forward end of said lever and of said blade.

4. In a buttonhole attachment for a sewing machine, a feed blade mounted for longitudinal and lateral movement, a stitch control lever located above said feed blade, means associated with the forward end of said lever connected with said feed blade, an upstanding tongue at the rear end of said lever, the upper portion of said tongue being of less width than the lower portion, a restriction bracket located above said lever, said bracket hinged at its forward end for up and down movement, a cross bar on said bracket, said cross bar having a slot, the length of said slot corresponding approximately to the width of the lower portion of said upstanding tongue, whereby said bracket will prevent oscillation of the rear end of said lever when said bracket engages the lower portion of said upstanding tongue, a spring normally holding said bracket out of engagement with the lower portion of said upstanding tongue, a cam wheel engaging said lever between the forward and rear ends of said lever and adapted to produce lateral oscillation of said lever, a horizontal rotating shaft located to the rear of said lever and bracket, a crank means connected with said shaft for producing longitudinal movement of said feed blade in alternate directions, a pair of bracket-engaging elements connected with said shaft and so arranged as to engage said bracket alternately and push said bracket to lowered position whenever said crank means has moved said blade to the end of its longitudinal path in either direction, whereby the pushing of said bracket to lowered position will cause greater lateral oscillation of the forward end of said lever and of said blade.

5. In a buttonhole attachment for a sewing machine, a feed blade mounted for longitudinal and lateral movement, a slot extending longitudinally in said feed blade, a stitch control lever located above said feed blade, a downwardly extending tongue on the forward end of said lever extending into said slot in said feed blade, an upstanding tongue at the rear end of said lever, the upper portion of said tongue being of less width than the lower portion, a restriction bracket located above said lever, said bracket hinged at its forward end for up and down movement, a cross bar on said bracket, said cross bar

having a slot, the length of said slot corresponding approximately to the width of the lower portion of said upstanding tongue, whereby said bracket will prevent oscillation of the rear end of said lever when said bracket engages the lower portion of said upstanding tongue, a spring normally holding said bracket in raised position so that only the upper narrower portion of said upstanding tongue will extend through said slot, a 10 slidable arm on said bracket, an adjustment lug on said arm, a cam wheel engaging said lever between the forward and rear ends of said lever and adapted to produce lateral oscillation of said lever, a horizontal rotating shaft located to the rear of said lever and bracket, crank means connected with said shaft for producing longitudinal movement of said feed blade in alternate directions, a disk mounted on said shaft, a pair of bracket-engaging elements carried by said disk and so arranged as to engage the end of said bracket arm when said arm has been adjusted so as to extend beyond the rear end of said bracket and push said bracket to lowered position whenever said crank means has moved said blade to the end of its longitudinal path in either direction, whereby the pushing of said bracket to lowered position will cause greater lateral oscillation of the forward end of said lever and of said blade.

6. In a buttonhole attachment for a sewing machine, a feed blade mounted for longitudinal and lateral movement, a slot extending longitudinally in said feed blade, a stitch control lever located above said feed blade, a downwardly extending tongue on the forward end of said lever

extending into said slot in said feed blade, an upstanding tongue at the rear end of said lever, a restriction bracket located above said lever, said bracket hinged at its forward end for up and down movement, a cross bar on said bracket, said cross bar having a slot, the length of said slot corresponding approximately to the width of said upstanding tongue, whereby said bracket will prevent oscillation of the rear end of said lever when said bracket engages said upstanding tongue, a spring normally holding said bracket out of engagement with said upstanding tongue, a slidable arm on said bracket, an adjustment lug on said arm, a cam wheel engaging said lever between the forward and rear ends of said lever and adapted to produce lateral oscillation of said lever, a horizontal rotating shaft located to the rear of said lever and bracket, crank means connected with said shaft for producing longitudinal movement of said feed blade in alternate directions, a pair of bracket-engaging elements connected with said shaft and so arranged as to engage the end of said bracket arm when said arm has been adjusted so as to extend beyond the rear end of said bracket and push said bracket to lowered position whenever said crank means has moved said blade to the end of its longitudinal path in either direction, whereby the pushing of said bracket to lowered position will cause greater lateral oscillation of the forward end of said lever and of said blade, and means for manually locking said arm and said bracket permanently in lowered position.

JAMES HICKEY.
